UNITED STATES PATENT OFFICE.

DOUGLAS F. FESLER, OF EVANSTON, ILLINOIS, ASSIGNOR, BY MESNE ASSIGNMENTS,
TO THE BASSICK MANUFACTURING COMPANY, A CORPORATION OF DELAWARE.

LUBRICATING APPARATUS.

1,361,375.

Specification of Letters Patent. Patented Dec. 7, 1920.

Application filed April 19, 1920. Serial No. 374,784.

To all whom it may concern:

Be it known that I, DOUGLAS F. FESLER, a citizen of the United States, residing at Evanston, in the county of Cook and State 5 of Illinois, have invented a certain new and useful Improvement in Lubricating Apparatus, of which the following is a full, clear, concise, and exact description, reference being had to the accompanying drawings, 10 forming a part of this specification.

My invention relates to improvements in lubricating apparatus and is especially concerned with improvements in that type of lubricating apparatus wherein each bearing 15 of the machine to be lubricated is provided with a lubricant receiving nipple, comprising means for establishing a detachable connection with a source of lubricant under pressure, so that lubricant under high pressure, 20 sure can be forced into the nipple.

The objects of my invention are—

First; to provide a cap for nipples of lubricating system, such as described above, for excluding dirt, dust and moisture from 25 the interior of the nipple and for protecting the spring-pressed closure thereof.

Second; to provide a closure of the character described so constructed that it can be easily attached to and detached from the 30 nipple.

Third; to provide a cap of the character described, comprising means for yieldingly holding the cap against movement longitudinally of the nipple in either direction and 35 thereby preventing the cap from rattling on the nipple, and

Fourth; to provide a cap of the character described which is simple in construction and economical to manufacture.

Other objects will appear as this description progresses, reference being had to the accompanying drawings, in which—

Figure 1 is a side elevation of my improved cap.

Fig. 2 is a side elevation of my improved cap, showing it applied to a nipple.

Fig. 3 is a central longitudinal section through my improved cap showing it positioned on a nipple which is shown in side 50 elevation, and

Fig. 4 is an enlarged side elevation of my improved cap, and the nipple with which it co-acts, portions of the cap and nipple being broken away.

Throughout the several views similar ref-

erence characters will be used for referring to similar parts.

Referring to the drawings, reference character 5 indicates the end member of my improved cap, which is shown as being provided with a concavo-convex boss 6, to provide a clearance space between the end member and the spring-pressed closure 7 of the nipple.

The details of construction of the nipple 8 65 form no part of my invention, except in so far as these details co-act with certain elements of my improved cap.

The details of construction of the nipple illustrated herein are clearly disclosed in the 70 patent of Arthur V. Gullborg No. 1,307,733 and will not be described further except to state I make use of the ends 9 of the pin extending through the nipple for securing my cap thereto. A flange 10 depends from the 75 edge of the end member 5 and is provided with a pair of outwardly flaring slots 11, disposed diametrically opposite to each other and adapted to receive the ends 9 of the pin extending through the nipple.

At a point intermediate the ends of the slot, the edges thereof are recessed as shown at 12 to provide a locking seat, or rather a pair of locking seats for the ends 9 of the pin, extending through the nipple.

Referring to Fig. 4, it will be noted that the recesses 12 are curved on a diameter slightly less than the diameter of the end 9 of the pin extending through the nipple, thereby providing two points of contact 13 90 on each side of the pin. It will also be noted that the width of the slot between the recesses 12 and the outer end of the slot is less than the diameter of the pin. This means that when the cap is forced over the end of the nipple, the edges of the slot are sprung away from each other until the pin lies between the recesses 12 whereupon the edges spring toward each other and the pin is yieldingly confined against longitudinal 100 movement in either direction between the points of contact 13. There is, therefore, no possibility of the cap rattling upon the nipple and producing a disagreeable sound.

The slot extends inwardly beyond the recesses 12 and its inner end is circularly enlarged, as shown at 14. By thus extending the slot, I provide a construction which is less rigid and more yieldable than if the slot should end at the inner ends of the re- 110

cesses 12, thus making it easier to attach and detach the cap from the nipple.

It will be noted from an inspection of Fig. 3 that the space between the recesses 12 and the end piece of the cap is such that the end cap is held in spaced relation to the end of the nipple. As a result of this construction there is no danger of the end cap bearing against the closure 7 and there is no necessity for accurate machining of the cap 7 to permit the points 13 to contact properly with the pin.

While I have described the details of the preferred construction of my improved cap, it is to be clearly understood that my invention is not limited to these details, but is capable of other adaptations and modifications within the scope of the appended claims.

Having thus described my invention, what I claim is:—

1. The combination with a cylindrical nipple, having a pin projecting from one side thereof, of a cap for said nipple comprising an end piece and means for holding said end piece spaced from the end of said nipple comprising a flange depending from the edge of said end piece, and provided with an outwardly flaring slot opening through the edges thereof, the edges of said slot at a point intermediate the ends thereof being recessed on a diameter less than the diameter of said pin to provide a pair of spaced points of contact on opposite sides of said pin, the inner end of said slot being circularly enlarged.
  2. The combination with a cylindrical nipple, having a pin projecting from one side thereof, of a cap for said nipple comprising an end piece and means for holding said end piece spaced from the end of said nipple comprising a flange depending from the edge of said end piece, and provided with an outwardly flaring slot opening through the edges thereof, the edges of said slot at a point intermediate the ends thereof being recessed on a diameter less than the diameter of said pin to provide a pair of spaced points of contact on opposite sides of said pin.
  3. The combination with a cylindrical nipple, having a pin projecting from one side thereof, of a cap for said nipple comprising an end piece and means for holding said end piece spaced from the end of said nipple comprising a flange depending from the edge of said end piece and provided with a slot opening through the edges thereof, the edges of said slot at a point intermediate the ends thereof being recessed on a diameter less than the diameter of said pin to provide a pair of spaced points of contact on opposite sides of said pin.
  4. The combination with a cylindrical nipple, having a pin projecting from one
- side thereof, of a cap for said nipple comprising an end piece and means for holding said end piece spaced from the end of said nipple comprising a flange depending from the edge of said end piece and provided with a slot opening through the edges thereof, the edges of said slot at a point intermediate the ends thereof being provided with a pair of spaced points of contact on opposite sides of said pin.
5. The combination with a cylindrical nipple, having a pin projecting from one side thereof, of a cap for said nipple comprising an end piece and a flange depending from the edge of said end piece and provided with a slot opening through the edges thereof, the edges of said slot at a point intermediate the ends thereof being provided with a pair of spaced points of contact on opposite sides of said pin.
6. The combination with a nipple, of a cap therefor, comprising an end piece, a flange depending from the edge of said end piece and co-acting means on said flange and nipple for holding said end piece in spaced relation to the end of said nipple.
7. The combination with a nipple, of a cap therefor, comprising an end piece, a flange depending therefrom and comprising means for engaging a portion of said nipple and yieldingly holding said cap against movement longitudinally of said nipple in either direction.
8. A cap comprising an end piece, a flange depending from the edge of said end piece and provided with an outwardly flaring slot opening through the edge thereof, the edges of said slot at a point intermediate the ends thereof being recessed and the inner end of said slot being circularly enlarged.
9. A cap comprising an end piece, a flange depending from the edge of said end piece and provided with an outwardly flaring slot opening through the edge thereof, the edges of said slot at a point intermediate the ends thereof being recessed.
10. A cap comprising an end piece having a flange depending from the edge thereof, said flange being provided with a slot extending inwardly from the free edge thereof, the inner end of said slot being circularly enlarged.
11. A cap comprising an end piece having a flange depending therefrom, said flange being provided with an inwardly extending slot, the edges of which comprise spaced contact points.

In witness whereof, I hereunto subscribe my name this 13th day of April, 1920.

DOUGLAS F. FESLER.
